G. E. GRAVENSTINE

RADIATOR CAP

Filed Dec. 19, 1927

FIG. 1

FIG. 2

INVENTOR,
George E. Gravenstine,
BY Howard S. Smith,
Esq. ATTORNEY

UNITED STATES PATENT OFFICE.

GEORGE E. GRAVENSTINE, OF DAYTON, OHIO, ASSIGNOR TO THE S. H. THOMSON MANUFACTURING COMPANY, OF DAYTON, OHIO, A CORPORATION OF OHIO.

DESIGN FOR A RADIATOR CAP.

Application filed December 19, 1927. Serial No. 24,553. Term of patent 7 years.

To all whom it may concern:

Be it known that I, GEORGE E. GRAVENSTINE, a citizen of the United States, residing at Dayton, in the county of Montgomery and State of Ohio, have invented a new, original, and ornamental Design for a Radiator Cap, of which the following is a specification, reference being had to the accompanying drawing, forming part hereof.

Figure 1 is a front view, and Figure 2 is a side view of a radiator cap showing my new design.

I claim:

The ornamental design for a radiator cap, as shown.

GEORGE E. GRAVENSTINE.
